UNITED STATES PATENT OFFICE.

JAMES L. HOYT, OF TINLEY PARK, ILLINOIS, ASSIGNOR OF ONE-HALF TO WELLINGTON C. VAN WORMER, OF TINLEY PARK, ILLINOIS.

TRIPLE REFLECTOR FOR HEADLIGHTS.

Application filed July 12, 1922. Serial No. 574,371.

To all whom it may concern:

Be it known that I, JAMES L. HOYT, a citizen of the United States, residing at Tinley Park, in the county of Cook and State of Illinois, have invented a new and useful 5 Triple Reflector for Headlights, of which the following is a specification.

The invention relates to triple reflectors for the headlights of automobiles. The purposes of the invention are to provide a one-piece triple reflector adapted to be installed in the casings of headlights already in use without material change in the headlight casing; to provide a one piece reflector having 10 three primary reflecting surfaces in such relation to each other that a first strong bright light may be projected a long distance forwardly for rapid driving on a clear road, or a second strong light may be projected forwardly and downwardly at such angle to the plane of the road that the glare of the light will not dazzle persons traveling on the road in front of the light or may be dimmed for parking when only a 15 little light is required; to produce a triple reflector by pressing a single sheet of metal to the form shown and described, thus attaining rapid uniform production at a minimum cost; and to provide a triple reflector 20 salable as a separate article of manufacture which may be easily and quickly installed in headlight casings already in use.

I attain these purposes by the means illustrated in the accompanying drawing, in 25 which Fig. 1 is a front elevation, and Fig. 2 is a side elevation of a triple reflector embodying my invention installed in a headlight casing of usual construction. Fig. 3 is a vertical section through the same reflector and through the same headlight casing, taken on the line 3—3 of Fig. 1, this view shows also electric lamps and electrical connections of the lamps in operative 30 relation to the reflector; Fig. 4 is an enlarged fragmentary horizontal section taken on the line 4—4 of Fig. 2; and Fig. 5 is a horizontal section taken on the line 5—5 of Fig. 1. The same reference numerals and characters designate the same parts in all 35 the views.

Inasmuch as the invention relates to automobile accessories which must be sold under severe competitive conditions it is vitally important that the device shall be produced 40 at minimum cost of manufacture, shall be

dependable and satisfactory in use, and shall be so simple that a person of ordinary intelligence can easily and quickly install it in headlight casings already in use without injury to the headlight casings. 60

The letter A designates the triple reflector as a whole; the letter B designates a headlight casing, of usual construction, in which the reflector is installed; the letters C and C' designate electric lamps of any approved type; the letter D designates the electrical system controlling the operation of the lamps; the letter E designates the usual glass front of the headlight casing; and the letter F designates the usual bezel ring used 65 to hold the glass plate in the front of the headlight casing. 70

The parts, B. C. C'. D. E. and F. are of usual construction and are shown only to illustrate the relation of the triple reflector 75 to the headlight casing and to show the mode of attaching and using the reflector.

The triple reflector A. is pressed from a single sheet of metal by suitable dies, and comprises an upper concavo-convex member 80 6, a lower concavo-convex member 7, an intermediate member 8 merged into the members 6 and 7 at their juncture; an inclined flat member 9 merged into the member 6; and a circular outwardly projected flange 85 member 10 merged into the members 6, 7 and 9 and extending entirely around the front or largest circumference of the reflector. The member 8 extends part way around the middle or waist of the reflector 90 and on each side merges into the inner wall of the reflector. Openings 16 at the central or focal points of the members 7 and 6 accommodate electric lamps C and C'. The lamps may be of any approved type and may 95 be energized by electric current from a source D of any approved type.

An electric switch 12 controls the operation of the lamp C and similar switches 13 and 14 may be used selectively to control 100 the operation of the lamp C'. Resistance 15 in the circuit of the switch 14 and the lamp C' serves to dim the lamp C' when desired.

To install the reflector in the casing of a headlight that is already in use, it is only necessary to detach the bezel ring, remove the glass and the reflector originally in the casing, substituting for it the triple reflector A, placing it in such position that its circular flange member 10 will rest even- 105 110

ly on the circular front edge of the casing; and then replace the glass front and the bezel ring to secure the triple reflector in place in the casing.

5 Having fully described my invention what I claim as new and desire to secure by Letters Patent is:

1. The article of manufacture, a triple reflector comprising in one piece, a first concavo-convex reflecting member having a lamp opening at its vertex; a second concavo-convex reflecting member having a lamp opening at its vertex; a waist-member merged into both of said concavo-convex members; a flat reflecting member inclined upwardly and outwardly from the vertex of and merged into said second concavo-convex member; and a flat circular rim-member at right angles to the extended axes of both concavo-convex members and merged into both concavo-convex members and into said inclined reflecting member.

2. A unitary triple reflector comprising a lower concave member having a central opening to receive an electric lamp; an upper concave member having a central opening to receive an electric lamp; a waist member merged into and intercommunicating with said lower and upper concave members; a flat inwardly inclined segmental

member merged into said upper concave member; and a flat circular rim member merged into said lower and upper concave members and into said inwardly inclined member and uniting all the members for convenient placing in a head light casing already in use.

3. A unitary triple reflector comprising a lower concave member, an upper concave member, a waist member intercommunicating with said lower and upper concave members, an inclined reflecting member merged into said upper concave member and a rim member uniting all of said members; in combination with a glaring electric lamp at the focus of said lower concave member; a non-glare electric lamp at a focus common to said upper concave member and said inclined reflecting member; means controlling the lighting and extinguishing of said glaring lamp, and means controlling the lighting, dimming and extinguishing of said non-glare lamp.

In witness whereof I have hereunto signed my name at Tinley Park, Illinois this 10th day of July 1922.

JAMES L. HOYT.
